UNITED STATES PATENT OFFICE

95,339

DESIGN FOR A COMBINED MAIL BOX AND SUPPORT THEREFOR

Herman Hahn, Olmsted Falls, Ohio

Application February 4, 1935, Serial No. 55,231

Term of patent 14 years

To all whom it may concern:

Be it known that I, Herman Hahn, a citizen of the United States, residing at Olmsted Falls, in the county of Cuyahoga and State of Ohio, have invented a new, original, and ornamental Design for a Combined Mail Box and Support Therefor, of which the following is a specification, reference being had to the accompanying drawing, forming part thereof.

design, the opposite side presenting substantially the same appearance as the one shown;

I claim:

The ornamental design for a combined mail box and support therefor substantially as shown and described.

HERMAN HAHN.
